UNITED STATES PATENT OFFICE

WATERS S. DAVIS, OF GALVESTON, TEXAS.

IMPROVEMENT IN COTTON-BALE TIES.

Specification forming part of Letters Patent No. 154,229, dated August 18, 1874; application filed July 22, 1874.

To all whom it may concern:

Be it known that I, WATERS S. DAVIS, of Galveston, in the county of Galveston and State of Texas, have invented an Improved Bale-Hoop Tie, of which the following is a specification:

My invention relates to an improved means of fastening the hoops or bands of cotton or other bales; and it consists in a plate provided with a slot and a raised loop, in combination with a tongue provided with a neck and T-head, whereby the plate is held securely in place on the hoop or band without depending therefor upon the elasticity of the bale, and the hoop or band is readily and securely fastened by the engagement of the T-head on the tongue with the slot in the plate.

In the accompanying drawing, Figure 1 is a perspective view of my improved fastening, showing the manner of attaching the plate to the hoop or band. Fig. 2 is a perspective view, showing the parts coupled together. Fig. 3 is a top view, showing the manner of coupling the plate and tongue. Fig. 4 is a longitudinal section through the hoop or band and fastening device.

The hoop or band C is made of the ordinary hoop-iron in the usual way. The plate A is provided with a slot, a, and a raised loop, b, and, preferably, is formed at one operation by striking it out of sheet metal with dies or other suitable tools or machinery. The loop b is formed with its inner side a sufficient distance from the plane of the surface of the plate to freely admit the passage of the hoop or band through the loop. The tongue B is provided with a neck, c, and a T-head, d, and is formed by striking it out of sheet metal, as described in regard to the plate A. The neck c corresponds with the width of the slot a in the plate, and the head d is wider than said slot, as shown in full lines in Fig. 1, and in dotted lines in Figs. 2 and 3. The neck c is bent or curved, forming an offset, e, so as to depress the head, and allow it to pass through the slot and lie flat under the plate A, as shown

in Fig. 4. The tongue B is preferably riveted to the hoop or band, thus saving several inches of hoop-iron in each band, which would be bent back if passed through a slot in the ordinary way. The plate A is attached to the hoop or band C by passing the end of the band through the loop and sliding the plate along said band, with the slotted portion foremost, as shown in Fig. 1, until a sufficient length of the band has passed through the loop. The plate A is then turned in the direction of the arrow shown in Fig. 1, so as to bend the hoop in the form and place the plate in the position shown in Figs. 2 and 4, when the parts are ready to be coupled, which operation is performed by inserting one arm of the T-head in the slot a, and then turning it, as shown in Fig. 3, until the other arm of the head is free to pass through the slot and slip under the plate, and lie flat, when the hoop or band is straightened out, as shown in Figs. 2 and 4.

The bend of the hoop being formed around the raised loop, it is held securely in place without depending on the elasticity of the bale.

I claim—

1. The plate A, provided with a slot, a, and raised loop b, in combination with the tongue B, provided with a neck, c, and head d, substantially as and for the purpose herein described.

2. The tongue B, riveted to the hoop C, and provided with a head, d, and neck c, in combination with the plate A, provided with a slot, a, which at some part of its length is of less width than the head d, and with a loop or eye for the hoop C to pass through, substantially as and for the purpose herein specified.

3. The offset e in the neck of the tongue B, in combination with the slot a in the plate A, substantially as and for the purpose herein set forth.

WATERS S. DAVIS.
